Primary Examiner—Joel Sincavage*Attorney, Agent, or Firm*—Terry M. Germstein[57] **CLAIM**

The ornamental design for a multi-outlet electrical receptacle, as shown and described.

DESCRIPTION

FIG. 1 is a front, top and side perspective view of the multi-outlet electrical receptacle embodying the design of the present invention;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom plan view thereof;

FIG. 7 is a perspective view thereof in the open condition; and,

FIG. 8 is a perspective view thereof, in the open condition.
